UNITED STATES PATENT OFFICE.

SVEN J. NORDSTROM, OF SAN FRANCISCO, CALIFORNIA.

THROTTLE-CONTROL DEVICE.

Application filed May 18, 1925, Serial No. 30,915.

To all whom it may concern:

Be it known that I, SVEN J. NORDSTROM, a subject of the King of Sweden, and a resident of the city and county of San Francisco, State of California, have invented certain new and useful Throttle-Control Devices, of which the following is a specification.

This invention relates to an improved means for controlling the operation of engine throttles, and is especially adapted for use on automobiles. In automobiles the throttle is usually controlled by an accelerator which is conveniently located on the foot-board for operation by the foot and means are provided for restoring the throttle to a closed position when the foot pressure is removed from the accelerator. When the driver of an automobile applies foot pressure to the accelerator to hold it in an intermediate position he finds it difficult to hold it constantly in one position due to the jolting of the car from various causes which tends to cause his foot to vibrate the accelerator, thereby intermittently applying the gas to the engine and causing the automobile to jump or lunge. The undesirable results occasioned by the intermittent and undesired depression of the accelerator are well known and need not be further referred to.

An object of the invention is to provide an improved device of this character which will operate in a safe and reliable manner.

Another object of the invention is to provide a throttle control device which is capable of universal use regardless of the type of car and which may readily be placed in operative position without disturbing any of the present throttle control mechanism of the car.

The invention possesses other advantageous features, some of which with the foregoing, will be set forth at length in the following description where I shall outline in full that form of the invention which I have selected for illustration in the drawings accompanying and forming part of the present specification. In said drawings I have shown several forms of devices embodying my invention but it is to be understood that I do not limit myself to such forms, since the invention as set forth in the claims may be embodied in a plurality of other forms.

In the drawings:

Figure 1 is an elevation of parts of a carburetor of an automobile illustrating the

throttle and accelerator mechanism with a throttle control device, embodying one form of my invention, shown in section, as applied to a push rod type of accelerator. 60

Fig. 2 is an enlarged sectional view illustrating the valve of the device shown in Fig. 1.

Fig. 3 is a vertical section illustrating a modified type of the form of device shown in Fig. 1 in which the valve is omitted. 65

Fig. 4 illustrates another form of device embodying my invention positioned alongside of the accelerator; and

Fig. 5 illustrates a form of device similar to that shown in Fig. 4 used with a foot pedal type of accelerator. 70

In Fig. 1 there are shown parts of an automobile carburetor including an air intake 1, a manifold 2 and a throttle valve 3 positioned within the intake 1. The throttle valve 3 is carried by a rotatable shaft 4, which is rotated by a crank arm 5 secured thereto. The movement of the crank arm 5 is limited by an adjustable stop 6 to prevent the complete closure of the intake by the throttle valve in the usual manner. The crank arm 5 is connected by a control rod 7 with one arm of a crank lever 8, which is pivoted at 9. The other arm of the crank lever 8 is provided with a slot 10 to accommodate a pin 11 on accelerator 12 which is of the push rod type. The accelerator 12 extends through an opening 13 in the foot board 14 of an automobile, and is slidably supported on the under side of said board by a guide member 15 as shown in Fig. 1. The upper end of the accelerator is provided with a button or knob 16 for convenience in foot operation. A spring 17 secured at one end to the crank arm 5, and secured at its other end to some fixed convenient point on the automobile, not illustrated, normally urges the throttle valve 3 to its closed position, as indicated in Fig. 1, and through the connections described, raises the accelerator to its extended or uppermost position. The parts thus far described comprise the usual throttle control mechanism and do not per se form a part of my present invention. 90

In operation, the automobile driver applies foot pressure to the accelerator 12 and when driving endeavors to maintain the same in an intermediate position; however, as above set forth, due to jolts from various causes, the accelerator is vibrated, thus causing the car to suddenly jump or lunge in a well un- 100

derstood manner. In order to overcome this difficulty I have provided an improved device designed to absorb these undesirable and sudden jolts and avoid the transmission 5 of the same to the throttle valve, without interfering with the normal operation of the same. This device comprises a resilient spherical hollow member 18, preferably of rubber, which has two diametrically opposite openings 19, 20, to receive the accelerator 12. Preferably, member or ball 18 is provided with internal collars 21, 22 around the openings, 19, 20, respectively, so as to closely fit around the accelerator 12 and prevent leakage. The member 18 is provided 10 with a valve 23 which is seated to rapidly admit air to the member 18 after it has been depressed so that it may rapidly expand and resume its normal position, but which closes when the member 18 is depressed. In order 15 to permit the member 18 to be slowly depressed, a small discharge passage 25 through the stem 24 of said valve is provided. As shown in Fig. 1, the ball or member 18 is positioned on the accelerator between the foot board 14 and the knob 16, so that when foot pressure is applied to the accelerator 12, the member 18 is slowly depressed, its movement being retarded by the 20 limited escape of air through the restricted passage 25 in the valve 23, and when foot pressure is removed from the accelerator 12, it is rapidly restored to its raised position 25 through the action of spring 17, the rapid expansion of the member or ball 18 being possible since the valve 23 is now open.

In view of the foregoing detailed description of a device embodying my invention, its operation will be readily understood 40 from a brief description thereof.

If the throttle valve 3 is in its closed position as shown in Fig. 1, it can be opened to any desired degree by applying foot pressure on the knob 16. While the member 18 45 does not interfere with the normal operation of the throttle valve, it prevents the same from being opened too fast by opposing the downward movement of the accelerator. By this opposition, undesirable pressures on the accelerator due to jolts from 50 rough roads and other causes, are absorbed and not transmitted to the throttle valve in a well understood manner.

In Fig. 3 I have shown a modified type of 55 device embodying my invention. Herein, the shock absorbing element 18', which corresponds to the member 18 in Fig. 1, is positioned in a similar manner on the accelerator 12. In this form of device, the internal collars 21 and 22 and the valve 23 have 60 been omitted, and the ball 18' is provided with simple openings 19' and 20' for the accelerator. Since the collars 21 and 22 have been omitted, there is sufficient leakage 65 through the openings 19' and 20' to make the

valve 23 unnecessary. Otherwise, the operation of this embodiment of the invention is similar to that described in connection with Fig. 1.

In Fig. 4 I have shown another form of 70 device embodying my invention. Herein, the member 18'', which corresponds to the member 18 in Fig. 1, is provided with a corresponding valve 23'' and instead of the accelerator extending through the same, said 75 member 18'' is suitably supported such as in a hemispherical cup 26, alongside of the accelerator 12, so that the driver's foot, as indicated at 27, may rest on the knob 16 and ball 18'' simultaneously. In this arrangement, the member 18'' opposes the sudden or rapid downward movement of the accelerator 12, in a manner similar to that above described.

If, instead of the push rod type of accelerator as above described, a foot pedal type of accelerator is used, such as is shown at 28 in Fig. 5, a shock absorbing member 18'', supported in a cup 26, such as is shown in Fig. 4, may be readily used, in which case, 90 the member 18'' and cup 26 are positioned underneath the foot pedal as shown in Fig. 5.

It will therefore be seen that my improved device may be readily applied to either type of accelerator, without disturbing 95 any of the throttle control mechanism.

I claim:

1. A device of the character described comprising an accelerator and a hollow member of resilient material having leakage means, said member being positioned to oppose the rapid movement of the accelerator in one direction. 100

2. A device of the character described comprising an accelerator and means opposing the rapid movement of the accelerator in one direction comprising a hollow member of resilient material having a valve. 105

3. A device of the character described comprising an accelerator and means opposing the rapid downward movement of the accelerator comprising a hollow spherical member of resilient material having a valve. 110

4. A device of the character described comprising an accelerator and means controlling the movement of said accelerator comprising a hollow member of resilient material having means for opposing the rapid movement of said accelerator in one direction and permitting its rapid movement in the opposite direction. 115

5. A device of the character described comprising an accelerator, and a rubber ball arranged to oppose the rapid movement of the accelerator in one direction having a valve. 120

6. A device of the character described comprising an accelerator, and a rubber ball having a valve arranged to oppose the rapid 125

movement of the accelerator in one direction and permit its rapid movement in the opposite direction.

7. A device of the character described comprising an accelerator of the push rod type extending through the foot board of an automobile, and having at its free end means adapted to be engaged by the foot of the driver, and a hollow member of resilient material having a valve, said member being positioned between said means and said foot board opposing the rapid downward movement of said accelerator.

8. A device of the character described comprising an accelerator of the push rod type extending through the foot board of an automobile, and having at its free end means adapted to be engaged by the foot of the driver and a rubber ball, having leakage means positioned between said means and said foot board.

9. A device of the character described comprising an accelerator of the push rod type extending through the foot board of an automobile, and having at its free end means adapted to be engaged by the foot of the driver and a rubber ball positioned between said means and said foot board, said accelerator extending through said ball.

10. A device of the character described comprising an accelerator of the push rod type extending through the foot board of

an automobile, and having at its free end means adapted to be engaged by the foot of the driver and a rubber ball positioned between said means and said foot board, said rubber ball having an air valve arranged to close when the ball is depressed and to open when the ball expands.

11. A device of the character described comprising an accelerator of the push rod type extending through the foot board of an automobile, and having at its free end means adapted to be engaged by the foot of the driver and a rubber ball positioned between said means and said foot board, said rubber ball having an air valve arranged to admit air freely when the ball expands and to permit a slow discharge of air from the ball when it is depressed.

12. A device of the character described comprising an accelerator extending through the foot board of an automobile and having a knob at its free end, a rubber ball positioned between said foot board and said knob, said accelerator passing through said ball, collars on said ball surrounding said accelerator to prevent leakage from the ball and an air valve in said ball arranged to permit a slow discharge of air therefrom when the ball is depressed and to admit air rapidly to said ball when it expands.

In testimony whereof, I have hereunto set my hand.

SVEN J. NORDSTROM.
